[57] CLAIM

The ornamental design for a magazine slide projector, substantially as shown and described.

DESCRIPTION

FIG. 1 is a front elevational view of a slide projector magazine showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a top perspective view thereof;

FIG. 8 is a bottom perspective view thereof; and

FIG. 9 is a cross-sectional view thereof.

FIG. 1

FIG. 2

FIG. 3

FIG. 5

FIG. 6

FIG. 8

FIG. 9
